Term of patent 14 years

Int. Cl. D12—02

U.S. Cl. D14—3

FIG. 1 is a top plan view of a portable fishing cart showing my new design, with the side door being in the open position;

FIG. 2 is a front elevation view thereof;

FIG. 3 is a left side elevation view thereof, with the lid being in the open position; and

FIG. 4 is a perspective view thereof, with the side door and the lid being in the open position.

The lid and the side door are shown fragmentarily in FIGS. 1 and 3, respectively, for convenience of illustration only. The rear and right side surfaces of the portable fishing cart, not shown, are solid and flat.

I claim:

The ornamental design for a portable fishing cart, as shown and described.
